DESIGN FOR A COMBINED HANDBAG AND GLOVE CONTAINER THEREFOR

A. Edward Browner, New York, N. Y.

Application December 30, 1937, Serial No. 73,994

Term of patent 3½ years

To all whom it may concern:

Be it known that I, A. Edward Browner, a citizen of the United States of America, residing in Manhattan, county of New York, and State of New York, have invented a new, original, and ornamental Design for a Combined Handbag and Glove Container Therefor, of which the following is a specification, reference being had to the accompanying drawing, forming part thereof, wherein,

Figure 1 is an end elevational view of a combined handbag and glove container therefor showing my new design.

Figure 2 is a front view of the handbag shown in Figure 1.

The rear portion of the handbag is substantially the same as the front with the exception of the tab closings.

The glove compartment opens at the side of the handbag, as shown in Figure 1.

I claim:

The ornamental design for a combined handbag and glove container therefor, substantially as shown, and described.

A. EDWARD BROWNER.
